LIGHT-CONTROLLED WAVEGUIDE ATTENUATOR

Benjamin Kazan, Princeton, N. J., assignor to Radio Corporation of America, a corporation of Delaware

Application April 20, 1954, Serial No. 424,400

8 Claims. (Cl. 333—81)

This invention relates to an attenuator for use in a waveguide carrying radio frequency energy, and particularly to a waveguide attenuator which is controlled by means of light.

It is often desirable to control the amount of radio frequency energy which is allowed to pass thru or past a given point in a waveguide. Most of the known means for accomplishing this purpose include a physical device which may be adjustable in position. Of course, a physical device does not lend itself to being moved rapidly and faithfully in response to a controlling force.

It is an object of this invention to provide a variable attenuator for use in a waveguide which is capable of varying the attenuation over a broad range at a very rapid rate in response to an electrical control signal.

It is another object of this invention to provide a waveguide attenuator including a photoconductive material which changes in conductivity in accordance with the amount of light falling thereon.

It is a further object of this invention to provide a forked waveguide including means to rapidly vary the proportion of the energy directed along the two forks.

It is a further object to provide an improved means for varying the amount of reflected radio frequency energy from a given point in a waveguide.

It is a still further object to provide a novel means for automatically controlling to a predetermined value the amount of radio frequency energy delivered by a waveguide.

In one aspect, the invention comprises a waveguide having a dielectric or insulating sheet disposed in the waveguide in the direction of the electric vectors of the radio frequency energy propagated therethru. The dielectric or insulating sheet is covered on one side with photoconductive crystals or a photoconductive powder. A light source external of the waveguide is oriented with relation to an aperture in a sidewall of the waveguide so that light in varying amounts may be directed onto the photoconductive material. The photoconductive material has a very high resistance in darkness, and the resistance decreases as a function of the amount of light which falls on the photoconductive material. With a maximum amount of light directed to the photoconductive material, the resistance of the material is so low as to permit currents therein, and to thereby attenuate or reflect radio frequency energy passing thru the waveguide.

Features of the invention include an arrangement whereby a photoconductive material is mounted in a gap structure in the waveguide; a forked waveguide arrangement whereby the division of radio frequency energy in the two forks is readily controllable; and a constant power output waveguide arrangement wherein the attenuation of energy in the waveguide is automatically controlled to provide a constant predetermined output.

These and other objects and aspects of the invention will be apparent to those skilled in the art from the more

detailed description taken in conjunction with the appended drawings wherein:

Figure 1 is a perspective view of a section of the waveguide including an attenuator constructed according to the teachings of this invention;

Figure 2 is a cross section of a waveguide including a modified form of attenuator;

Figure 3 is a view of a forked waveguide wherein each of the forks includes a light-controlled waveguide attenuator for controlling the division of energy in the two forks; and

Figure 4 is an illustration of a waveguide including means to automatically maintain a constant radio frequency output power therefrom.

Figure 1 shows a light-controlled waveguide attenuator. The waveguide 10 is the conventional rectangular metallic waveguide thru which radio frequency electrical energy may be propagated with the electric field vector extending in the vertical direction between the greater sidewalls 11 and 12. Waveguides of other shapes may, of course, be employed provided that consideration is given to the direction of the electric field vector in the waveguide. A sheet 13 of dielectric or insulating material is mounted in the waveguide to extend vertically between the greater sidewalls 11 and 12 and to extend longitudinally thru the waveguide for a limited distance. The insulating or dielectric sheet 13 does not significantly interfere with or effect the propagation of radio frequency energy thru the waveguide.

One side of the insulating sheet 13 is coated with a layer 14 of photoconductive crystals or a photoconductive powder. The photoconductive particles may or may not be arranged so that they contact each other and form a surface extending from the greater sidewall 11 to the greater sidewall 12. Any suitable bonding technique may be employed to support the photoconductive particles. The bonding material may be such as to provide a self-supporting structure so that an insulating sheet 13 is not needed.

The smaller sidewall 15 of the waveguide 10 is provided with an aperture 16. A light bulb 17, or other source of light, is disposed outside the waveguide 10 and is oriented with relation to the aperture 16 and the photoconductive layer 14 so that light from the source 17 may be directed thru the aperture 16 to the layer 14. The amount of light directed from the source 17 to the layer 14 may be varied by varying the electric current applied to the light source 17 or by placing a controllable light barrier, for example an opaque shutter, between aperture 16 and source 17.

In the operation of the attenuator of Figure 1, radio frequency energy is directed or propagated along the waveguide 10 in the direction of the arrow 18. When the light source 17 is deenergized and no light falls on the photoconductive layer 14, the photoconductive layer has a very high resistance so that it is in effect an insulator. Under this condition, the radio frequency energy propagated thru the waveguide is unaffected by the presence of the photoconductive layer 14 therein. When light from the source 17 is directed to the photoconductive layer 14, the layer 14 becomes conductive as a function of the amount of light falling thereon. When the photoconductive layer 14 becomes conductive, the radio frequency energy in the waveguide 10 is to some extent dissipated in the conductive layer 14 and is therefore prevented from being propagated undiminished thru the waveguide. It is apparent that the resistivity of the layer 14 is a function of the amount of light falling thereon, and that the amount of radio frequency energy propagated thru the waveguide may be controlled by controlling the amount of light from the source 17. Variations in the attenua-

tion in the waveguide may be made as rapidly as the light source 17 may be varied in intensity; subject only to the limitations of the response time of the particular photoconductive material employed.

Figure 2 shows a modified form of the invention wherein in the greater sidewalls 11' and 12' of the waveguide 10' are provided with conductive protuberances 20, 21 to form a gap structure therebetween. A crystal 22 of photoconductive material is mounted in the gap formed by the protuberances 20 and 21. Light is directed from a source (not shown) thru an aperture 16' to the crystal 22. The gap structure is such as to concentrate or intensify the radio frequency electric field across the crystal 22. Varying amounts of light falling on the crystal 22 produce varying degrees of attenuation of the radio frequency energy.

In Fig. 2, the photoconductive crystal 22 may be a single crystal member, or may be a capsule of crystal particles held in place by a transparent shell or by a suitable bonding agent. The gap structure and the photoconductive material therein may be elongated to extend an appreciable distance along the length of the waveguide. In Figure 2, a metallic screen 25 is placed over the aperture 16' to prevent the escape of radio frequency energy from the waveguide thru the aperture 16'. The screen allows light to pass thru while confining the radio frequency energy in the waveguide. On the other hand, the aperture 16' may be made sufficiently small so that radio frequency energy cannot escape even though the metallic screen 25 is omitted.

Figure 3 shows a waveguide 26 which is forked to provide two branches 27 and 28. Each of the branches is provided with a layer of photoconductive material supported by an insulating sheet after the manner described in connection with Figure 1. A light source 29 is associated with one branch 27 and a light source 30 is associated with the other branch 28. Radio frequency energy which passes thru the waveguide 26 may be directed to either the branch 27 or the branch 28 by the synchronous operation of the light sources 29 and 30. When light source 29 is on and light source 30 is off, energy is directed thru the branch 28. Conversely, when light source 30 is on and light source 29 is off, energy is directed thru the branch 27.

Referring to Figure 4, a waveguide 32 is provided with a photoconductive layer 33 which may be illuminated thru an aperture 34 from a light source 35. A radio frequency detector 36 has an input coupled by means of a coupling loop 37 in the interior of the waveguide 32. The output of the radio frequency detector 36 is applied to a power amplifier 38. The output of the power amplifier is applied over leads 39 to the light source 35.

In operation, radio frequency electrical energy is applied to the waveguide 32 at the left end thereof, from which it is propagated past the photoconductive layer 33, and then past the coupling loop 37 to the output end 40 of the waveguide. A constant value of radio frequency power may be delivered from the output end 40 of the waveguide 32 while a varying amount of power is applied to the input end 41. When a greater than predetermined value of radio frequency energy is coupled from the waveguide by the coupling loop 37, the radio frequency detector 36 generates a signal which is amplified in power amplifier 38 and applied over leads 39 to the light source 35. The light from the source 35 is thus increased to cause the resistance of the photoconductive layer 33 to decrease. As a result, radio frequency energy is attenuated until the desired predetermined value of energy is delivered at the output end 40 of the waveguide 32. It is apparent that the system operates as an automatic power control to maintain a constant power output regardless of variations in the input power to the waveguide.

There are various photoconductive materials well known in the art which are suitable for use in the attenu-

ators of this invention. Cadmium sulphide is one of the well known photoconductive materials which have been found to be particularly suitable.

The term "waveguide" as used herein is not limited to waveguides of the type commonly used for the transmission of radio frequency energy from one point to another. The term "waveguide" is intended to include structures of all kinds thru which radio frequency energy is propagated with the electric field vector in a predetermined orientation.

What is claimed is:

1. A light-controlled waveguide attenuator comprising a waveguide having opposed walls through which radio frequency energy may be propagated, photoconductive material in said waveguide, a support for said photoconductive material positioned between said walls, one of said walls being provided with an aperture therein, said aperture being in a position to permit light from a source to fall upon said photoconductive material so that said material serves to attenuate radio frequency energy passing through said waveguide.
2. A light-controlled waveguide attenuator comprising a waveguide through which radio frequency energy may be propagated, said waveguide being rectangular in shape and having greater and lesser side walls, one of said lesser side walls being provided with an aperture therein, photoconductive material positioned in said waveguide and extending from one of said greater side walls to the other of said greater side walls, and a light source external of said waveguide, said aperture being in a position to permit light from said source to fall upon said material so that said material serves to attenuate radio frequency energy passing through said waveguide.
3. A waveguide attenuator as defined in claim 1, wherein said photoconductive material is in the form of photoconductive powder, and in addition a dielectric sheet in said waveguide supporting said powder.
4. A waveguide attenuator as defined in claim 1, wherein said light source is electrically operated, and in addition, a variable source of electricity connected to energize said light source.
5. A waveguide attenuator as defined in claim 1, wherein said light source is electrically energized, and in addition, a radio frequency detector having an input coupled to the interior of said waveguide, and a power amplifier having an input coupled to the output of said detector, and having an output coupled to said light source, the intensity of said light source being responsive to said output of said detector, whereby the radio frequency energy passing thru said waveguide is automatically controlled.
6. A waveguide attenuator comprising, a waveguide having opposed walls, conductive protuberances extending from opposite walls of said waveguide to form a gap therebetween, one of said walls being provided with an aperture therein, photoconductive material disposed in said gap and in contact with both of said protuberances, and means external of said waveguide to direct varying quantities of light through said aperture to said photoconductive material.
7. In combination, a waveguide having a junction point from which two waveguide branches extend, each of said branches having a wall with an aperture therein, a sheet of photoconductive material in each of said branches extending in the direction of the electric field vectors therein, and means external of said waveguide to direct light through said apertures to said photoconductive sheets in said branches, whereby the radio frequency electric energy passing thru said two-branches may be varied by varying the light directed thereto.
8. A light-controlled waveguide attenuator comprising a waveguide having opposed walls through which radio frequency energy may be propagated, a light source external of said waveguide, one of said walls being con-

structed to permit light from said source to be transmitted through a portion thereof, a sheet of photoconductive material positioned in said waveguide to receive light from said source, said photoconductive material being positioned so that its surface is substantially parallel to the electrical field vector in said waveguide and so that when said material is illuminated by said light source it serves to attenuate radio frequency energy passing through said waveguide.
